UNITED STATES PATENT OFFICE.

CHARLES E. BARRETT, OF LAWRENCE, MASSACHUSETTS, ASSIGNOR TO
THE J. H. HORNE & SONS COMPANY, OF SAME PLACE.

SHAKE-RAIL FOR FOURDRINIER MACHINES.

SPECIFICATION forming part of Letters Patent No. 595,753, dated December 21, 1897.

Application filed November 27, 1896. Serial No. 613,633. (No model.)

To all whom it may concern:

Be it known that I, CHARLES E. BARRETT, of Lawrence, county of Essex, and State of Massachusetts, have invented an Improvement 5 in Shake-Rails for Fourdrinier Paper-Machines, of which the following description, in connection with the accompanying drawings, is a specification, like letters on the drawings representing like parts.

10 The present invention relates to a Fourdrinier paper-machine, and is embodied in a novel construction and arrangement of the supports for the shake-frame whereby a better action of said shake-frame is produced for 15 the proper laying of the fiber along the wire.

As heretofore constructed the shake-frame has been mounted upon arms or supports pivotally connected therewith at their ends, the result being that the shake-rails and table-rolls connected therewith when vibrated or moved from side to side travel on the arc 20 of a circle, the radius thereof being determined by the length of the supports for the shake-frame, so that an up-and-down or vertical movement is imparted to the pulp-support 25 in addition to the rectilinear movement. This up-and-down movement is objectionable and results not only in an imperfect laying 30 of the fiber, but also in a twisting and straining of the shake-rails, and the present invention is intended to obviate these difficulties by supporting the shake-frame in such a manner that the surface of the table-rolls, including that of the breast-roll, will be confined 35 in its movement to a horizontal plane in the vibration of the shake-frame without any up-and-down movement whatever.

In carrying out the invention the shake-frame, in which the breast-roll is mounted, is 40 supported at its movable end upon movable supporting members properly held in position and having cylindrical upper and lower surfaces, thus practically constituting rollers or rolling supports along which the shake-frame moves, so that in the lateral movement 45 thereof there is no vertical movement whatever, the desired result thus being accomplished and the construction at the same time simplified, the pivotal joints, moreover, being 50 dispensed with, so that wear is practically reduced to a minimum.

Figure 1 is a front elevation of the shake-frame, showing the supports therefor and the breast-roll. Fig. 2 is a side elevation of a sufficient portion of the machine to show the 55 general arrangement of the shake-rails and shake-frame; and Fig. 3 is a perspective view, on an enlarged scale, of the supporting member, which forms the main feature of the invention.

The shake-frame *a* is provided at its ends with uprights *a*², adapted to support the breast-roll *b*, the said uprights being preferably formed integral with the shake-frame. The shake-rails *c* are pivotally secured in any 60 suitable way at the top of the said uprights, as indicated at *c*² in Fig. 2, to provide for the movement of the shake-frame with relation to the stationary parts of the machine beyond it, the said shake-rails extending back to the 70 stationary support *A*, where they are pivoted at *c*³. The table-rolls *c*⁴ are mounted in bearings *c*⁵, connected to the shake-rails by hangers *c*⁶, these parts, together with the wire-gauze belt *c*⁷, (shown only in Fig. 2,) constituting what is known as the "wire" part 75 of a Fourdrinier machine. To provide for the lateral vibratory movement of the said shake-frame *a*, it is mounted, in accordance with the present invention, upon the top of 80 movable supporting members *d*, which are interposed between the lower surface of said shake-frame at the ends thereof and the floor or support *e*, upon which the machine is set up. The said members *d* have cylindrical 85 upper and lower surfaces *d*² and *d*³, the shake-frame *a* having flat bearing portions *a*³, resting upon the upper surface *d*², while the lower surface *d*³ rests upon the stationary support *e*, a shoe or supporting-plate *e*² being shown 90 as secured to the floor *e* to provide a proper bearing for the member *d*. The member *d*, therefore, practically constitutes, so far as the lateral movement of the shake-frame *a* is concerned, a rolling support upon which 95 the said frame moves back and forth, so that in the vibration thereof there is no lifting and lowering of the same as is the case when it is mounted at the end of swinging arms or pivoted supports, the movement of the wire 100 part being in a horizontal plane.

As herein shown, the shake-frame *a* is held

in position upon the supporting members d (there being one of said members at each end of the said frame) by means of coöperating engaging portions, the said frame a having 5 shoulders or projections a^4 , between which extends a tongue d^20 , there being, preferably, two of said tongues, one at each side of the support d , coöperating with two corresponding sets of projections a^4 at opposite sides of 10 the upright a^2 . In a similar manner the shoe e^2 is provided with a projection e^20 at each side thereof, extending upward between shoulders, shown as formed on lateral projections e^30 from the supporting member d , 15 the shoe e^2 being preferably provided with a bearing-surface e^3 , rising somewhat above the main surface thereof, with which bearing-surface the support d directly engages.

The shoes e^2 may be secured to the floor by 20 any suitable or usual means, it being obvious that the projections d^20 and e^20 keep the parts in proper operative position after they are once assembled, there being, practically, no pivotal joints or bearings to be taken care of, 25 while the vibration of the frame takes place in a straight instead of curved line of movement, with practically no frictional resistance, since it moves upon a rolling support.

The vibration of the frame may be provided for in any suitable way, the said frame 30 being herein shown as provided with a pitman f , secured to a lug or projection f^2 at the side thereof.

To prevent the shake-frame from rolling 35 off the supports if for any reason the pitman f is disconnected therefrom, the said supports are shown in Fig. 1 as provided with horns or projections d^4 , adapted to engage the under side of the shake-frame a in the rolling 40 movement of the supports if said movement is continued beyond the normal.

It is found that the rectilinear movement obtained by this construction and arrangement of the supports for the shake-frame 45 lays the fiber of the pulp to much better advantage, since the vertical movement, which is combined with the rectilinear movement in machines as heretofore constructed, tends to tip up the fibers and roughen the sheet, 50 such tendency being obviated by getting rid of the vertical movement. Difficulty is experienced also in such machines, owing to the fact that the peculiar movement due to the manner of supporting the shake-frame 55 results in a twisting of the shake-rails, tending to wear loose or break the pivotal connection thereof with the stationary portion of the machine. This difficulty is entirely obviated by the construction herein described, 60 which produces a movement of the shake-rails, confined to a horizontal plane perpendicular to the axis of the pivots, with no tendency to twist or strain.

The breast-roll is shown as secured to the 65 shake-frame on the inner side thereof or the side toward the stationary part of the ma-

chine, the construction being such that the bearings for the breast-roll are detachably secured to the shake-frame, so that it is not necessary to remove the breast-roll bearings from 70 the said roll in order to remove the roll from the machine. Since the breast-roll is on the inner side of the shake-frame, moreover, it is obvious that after it has been lowered it may be moved toward the stationary part of 75 the machine to slacken the wire-gauze belt, so that it is not necessary to disturb the tension-rolls, which are provided to keep the said belt tight.

The breast-roll is mounted in bearings b^2 80 at each end thereof, the said bearings being of any suitable construction, and each bearing is provided with a tongue b^3 , extending upward into an opening in an overhanging lug b^4 , secured, as by bolts b^5 , to the inner 85 side of the shake-frame. After the said tongue is inserted in the opening in the lug b^4 it is secured by means of a pin b^{10} , extending laterally through said lug, the said lug being also provided with a set-screw b^{11} to 90 prevent any lateral play of the projection b^3 in its socket.

The lug b^4 is shown as provided with a set-screw b^6 for the proper vertical adjustment thereof. When, therefore, it is necessary to 95 remove the breast-roll, the set-screw b^{11} is loosened and the pin b^{10} taken out, and the said breast-roll may then be lowered and moved inward or toward the stationary end 100 of the machine, so that it can be readily moved out endwise at the side of the machine.

I claim—

1. In a Fourdrinier paper - machine, the combination with the shake-frame and shake-rails pivotally secured thereto at one end, 105 and pivotally connected at their opposite ends to a stationary support, of stationary supporting plates or shoes for said frame, and movable supporting members having cylindrical upper and lower surfaces, said members being interposed between said frame and 110 said plates and provided with engaging portions coöperating with said frame and the stationary supporting-plate, substantially as described.

2. In a Fourdrinier paper - machine, the combination with the shake-frame, and means for producing a lateral vibratory movement thereof, of a rolling support therefor, and horns or projections from said support adapted 115 to engage said frame during a movement thereof beyond its normal lateral movement, and prevent further lateral movement thereof, substantially as described.

In testimony whereof I have signed my 125 name to this specification in the presence of two subscribing witnesses.

CHARLES E. BARRETT.
